UNITED STATES PATENT OFFICE

ERNST ALFRED GILDE, OF UNION CITY, NEW JERSEY

CLOTHESLINE SUPPORT

Application filed December 1, 1927. Serial No. 237,077.

This invention relates to a safety extension for clothes lines and has for its object to provide a novel and improved device attachable to the outside of a window sash or frame and adapted to be swung within the room so as to permit the clothes to be fastened on the said clothes line prior to its being carried outside the window sash.

One of the objects of my invention is to provide a safety device in the form of an arm having a pulley or roller on its inner end and over which the clothes line is trained, said arm being of a length to be fastened on the outside of the window sash or frame and swung within the room proper so that the clothes may be suspended and fastened to the line and carried outside the window sash.

To enable others skilled in the art to more fully understand and appreciate my invention and its practical application for the purpose and use intended, reference is had to the accompanying drawing in which

Fig. 1 is a side view showing my invention and its relation to the window sashes and window frame.

Fig. 2 is a plan of the device detached from the sash.

Fig. 3 is a sectional view taken on the line 3—3 of Fig. 1.

Fig. 4 is a partial perspective view showing the position of the line when the arm is in its inoperative position.

Referring now to the drawings wherein like reference characters designate corresponding parts throughout the several views, 5 designates the window sash or frame and 6, 7 the top and bottom windows through which the safety device is swung from the full line to the dotted line position shown by Fig. 1.

An extension arm 8 is provided at one end with a pair of parallel, flat bars 9, 10, riveted thereto as at 11 and extending beyond the extreme outer end thereof, said bars supporting a short shaft 12 on which a roller is mounted and over which the clothes line 14 is trained.

The opposite end of the extension arm is equipped with a swiveled eye bolt 15 passing therethrough, said bolt having an eye 16 forming a guide for the top strand of the line, the

lower end of said bolt being formed with an open hook 15^a on which the lower strand of the line may be supported as shown more clearly by Fig. 1. Pivotaly attached to the eye bolt is a U-shaped connector 17, said connector being in turn fastened to the interconnected, link 18 and screw eye 19, the latter being attached to the frame of the window.

In order to maintain the extension arm in its horizontal or operative position when projected within the room, the said arm is equipped with a screw eye 20 to which the hook 21 is fastened and adapted to engage the screw eye 22. By disconnecting the hook, the extension arm may be swung outwardly through the window and lowered to the dotted line position, after the clothes have been suspended on the line and carried outside the sash. In this position the window may be lowered without interference. On the other hand when it is desired to either remove the clothes or fasten the clothes on the line, the lower strand may be disconnected from the open hook 15^a, as shown in full lines by Fig. 1. This will produce slack in the lower strand of the line and permits the clothes to pass the hook portion 15^a of the bolt. When the lower strand is positioned on the hook, the arm may be projected out through the window and lowered to its inoperative or dotted line position.

It will be noted that the stress and strain is for the greater part placed on the eye bolt rather than the extension arm, so that the latter may be of very light material, such as wood, instead of providing a metal arm. If so desired, the roller 13 may be adjustably connected to the flat bars where it is desired to allow for stretching of the line.

While I have shown and described by invention with some degree of particularity, I realize that various alterations and changes in the details may be made. I therefore reserve the right to make such modifications in the structure as may fairly fall within the scope of the subject matter being claimed.

Having shown and described my invention, what I claim as new and desire to secure by Letters Patent is:

A clothes line support comprising an ex-

tension arm having a roller and means at its outer end for supporting said roller, and an eye bolt passing through the opposite end of said arm, said eye bolt constituting a guide for the top strand of a clothes line, a hook on the bottom of said eye bolt below the arm for supporting the bottom strand of said clothes line in one position, a U-shaped connector having its arms attached to the ends of said eye bolt and extending beyond the end of said arm, a link, and an interconnected screw eye fastened to said connector, said screw eye being attachable to the frame of a window and whereby said arm may be swung from a vertical, inoperative position to a laterally operative position through said frame of the window.

In testimony whereof I affix my signature.
ERNST ALFRED GILDE.
